UNITED STATES PATENT OFFICE.

LEO HOLLANDER, OF SALT LAKE CITY, UTAH TERRITORY.

DESIGN FOR A SPOON.

SPECIFICATION forming part of Design No. 21,656, dated June 28, 1892.

Application filed May 26, 1892. Serial No. 434,502. Term of patent 3½ years.

To all whom it may concern:

Be it known that I, LEO HOLLANDER, a citizen of the United States, residing at Salt Lake City, in the county of Salt Lake and Territory of Utah, have invented and produced a new and original Design for Spoons, of which the following is a description, reference being had to the accompanying drawing.

My invention relates to a design for spoons and the like, and it is illustrated in the accompanying drawing, in which the figure represents a plan view in perspective of my invention.

The leading feature of my design consists of a spoon having within its bowl a representation of the statue erected in Salt Lake City, Utah, to Brigham Young and the pioneers,

and provided with a handle widened at its upper end, within which enlarged part is placed the representation of the coat of arms of the Territory of Utah, comprising a beehive with bees resting thereon and flying about it. Entwined around the handle of the spoon is a festoon or garland of flowers, leaves, &c.

I claim as my invention—

The design for a spoon, substantially as herein shown and described.

In testimony whereof I affix my signature in presence of two witnesses.

LEO HOLLANDER.

Witnesses:

SHERMAN W. MOODY,
STARR PAGE.
